GLASS FILLER HEAD FOR LIQUID DISPENSERS

Myron S. Rapaport, New Rochelle, N.Y., assignor to
Kenco Products Corporation, a corporation of New
Jersey

Application April 24, 1958, Serial No. 50,593

Term of patent 14 years

(Cl. D91—3)

FIG. 1

FIG. 2

FIG. 3

Fig. 1 is a perspective view of a glass filler head for liquid dispensers showing my new design;

Fig. 2 is a front elevational view thereof on a reduced scale; and

Fig. 3 is a side elevational view of Fig. 2.

The end of the head opposite that shown in Fig. 2 is plain, and the side opposite that shown in Fig. 3 is identical with the view shown.

I claim:

The ornamental design for a glass filler head for liquid dispensers, as shown and described.
